CLAIM

The ornamental design for a bath spout as shown and described.

DESCRIPTION

FIG. 1 is a perspective view of a bath spout of the claimed design;

FIG. 2 is a top view thereof;

FIG. 3 is a bottom view thereof;

FIG. 4 is a side view thereof;

FIG. 5 is another side view thereof;

FIG. 6 is a front view thereof; and,

FIG. 7 is a rear view thereof.

The broken lines formed by equal length dashes indicate portions of the bath spout that form no part of the claimed design. The broken lines formed by unequal length dashes (i.e., dash-dot) indicate the bounds of the claim and form no part of the claimed design.
